WARNING DEVICE FOR LIQUID DISPENSING APPARATUS

Warren H. De Lancey, Springfield, Mass., assignor to Gilbert & Barker Manufacturing Company, West Springfield, Mass., a corporation of Massachusetts

Application May 3, 1937, Serial No. 140,367

5 Claims. (Cl. 221—95)

This invention relates to liquid dispensing pumps for gasoline and the like of the type in which an indicating register is provided for displaying the quantity of gasoline dispensed. For accurate service from such a pump it is desirable that the register be reset to zero before each new dispensing operation.

In the form employed with the present invention the register is reset to zero by a manual operation of the pump attendant independently of starting the pump. While the attendant can usually be relied upon to effect this manual operation of resetting before starting a dispensing operation, the present improvement is designed 15 to prevent the attendant from inadvertently neglecting the reset. In its general aspect the means provided for accomplishing this purpose comprises an audible signal such as a bell which rings only at such time as the pump may be 20 started for operation without having previously reset the register to zero. If on the other hand, the reset is performed before starting the pump no signal will be given. In other words, the normal and proper operation of the pump will 25 prevent the giving of any signal, and the attendant will be warned only, when by mistake he has neglected to operate the reset.

Furthermore, provision is made so that if the attendant starts up the pump without resetting 30 the register the bell will continue ringing until either the pump is stopped or the reset is made. The resetting operation if performed initially will prevent a subsequent signal, and if performed after starting the pump, will stop the signal so 35 that the dispensing may then be proceeded with in proper manner.

Referring more particularly to the drawings,

Fig. 1 is a front view of a complete pump with the front panel partly broken away to show 40 some of the interior parts;

Fig. 2 is a side view of the same showing some of the principal interior parts in dotted lines;

Fig. 3 is a view approximately full size of the 45 cocking and release mechanism for the bell signal showing the position of the parts with the motor switch off, the full line position of the toggle being prior to reset, and the dotted line position of said toggle being after a reset operation;

Fig. 3A is a view of the bell, the broken off connecting rod 19 in this view being understood as an extension of the rod 19 in Fig. 3;

Fig. 3B is a view of the motor switch, the 55 broken off connecting rod 13 in this figure being

understood as an extension of the rod 13 in Fig. 3;

Fig. 4 is a similar view with the motor switch on after a failure to reset whereby the bell is ringing; and

Fig. 4A is a view of the bell, the broken off connecting rod 19 in this view being understood as an extension of the rod 19 in Fig. 4;

Fig. 4B is a view of the motor switch, the broken off connecting rod 13 in this figure being 10 understood as an extension of the rod 13 in Fig. 4;

Fig. 5 is a similar view with the motor switch on after proper reset with the bell not ringing.

Fig. 5A is a view of the bell, the broken off connecting rod 19 in this view being understood as an extension of the rod 19 in Fig. 5;

Fig. 5B is a view of the motor switch, the broken off connecting rod 13 in this figure being 15 understood as an extension of the rod 13 in Fig. 5.

Referring more particularly to Figs. 1 and 2, the pump casing is indicated at 1, and within said casing are suitably arranged the operative parts of the pump comprising a combined motor 25 and pump unit 2 which draws liquid such as gasoline up through pipe 4 from a source of supply not shown, and drives it through an outflow pipe 5, fluid measuring meter 6, to a delivery hose 7 in the usual manner. The motor 30 switch for the motor 2 is contained within the casing 3. The nozzle guard 8 of the delivery hose 7 is adapted for resting on fixed support 9 at one side of the pump casing when said hose is not in use for dispensing. The operator's 35 handle for the motor switch is indicated at 10 as being fixed to a handle shaft 11 and a projection 10' of said handle 10 is arranged so that when the nozzle guard 8 is in its position of rest upon the support 9 the switch handle 10 cannot 40 be turned to on position. An arm 12 fixed to the handle shaft 11 is connected by link 13 to an arm 14 which operates the motor switch within the casing 3. In the position shown in Figs. 1 and 2 the handle 10 and motor switch are in 45 off position.

The pump motor has its shaft extended upwardly from the casing 2 to provide a rotating stub portion 15 suitable as a friction driving element. A mechanically operated signal bell 16 50 is carried on a swinging arm 17 pivoted at 18 on the frame of the pump casing and it will be understood that said bell is operated for ringing by the rotation of its friction wheel 15' when the latter is swung into running contact with the 55

rotating stub shaft 15. The supporting arm 17 for the bell 16 is connected by link 19 to one arm of a trip member 20, only a portion of which is shown in Fig. 2, and the more detailed operation 5 of which will be later described in connection with the other figures of the drawings.

Arranged within the pump casing is a suitable register indicator 22 which is operated through shaft 23 from the meter 6 whereby in the usual 10 manner said register will indicate the quantity of gasoline being dispensed through the hose 7.

The form of register 22 herein shown is of the well known computer type with dial indicators 24 for displaying the quantity of gasoline dispensed 15 both in terms of gallons and in money cost. 25 is a reset handle fixed to a reset shaft 26 and the latter extends across the pump casing so that one end of said shaft 26 is adjacent the trip member 20 above mentioned. It will be understood 20 that the reset shaft 26 is provided with the necessary elements for coaction with the register 22 to reset the dial figures thereof to zero whenever the handle 25 is rotated a complete revolution. These parts are well known and need not be 25 further described.

Referring more particularly to the Figs. 3, 4, and 5, these show in detail the several parts of the cocking and release mechanism for giving a signal. Pivotaly mounted at 28 on bracket 21 30 which in turn is fastened to the right side of the pump casing as viewed in Fig. 1, is the trip member 20. This is a two-armed lever, one arm 27 of which is connected by spring 29 to the bracket 21 whereby the trip member tends to rock in a clockwise direction. A stop lug 30 on said arm 27 limits the extent of this movement by abutting against the hub of a cam collar 31 which is fastened to the end of the aforesaid mentioned reset shaft 26. When the reset shaft 26 is 40 revolved to reset the register it turns in the direction of the arrow (Fig. 3) and during this revolution a cam 32 on the collar 31 acts against the stud 30 to latch the trip member 27 into the position shown in Fig. 3. This may be termed the 45 holding position of the trip member 27, since it holds the bell 16 out of ringing position. The trip member 27 is held in this holding position by a latch pawl 35 which is pivoted at 36 upon a rocking beam 33, the latter being pivotally mounted at 34 upon the bracket 21. A latch pawl spring 37 yieldingly holds the latch pawl 35 in its 50 position shown in Fig. 3.

A bifurcated segment plate 38 straddles the rocking beam 33 and is also pivoted at 34 upon 55 the bracket 21. The segment plate 38 carries therein studs or rollers 39, 40 and 41. Combined with the plate 38 to form a toggle is a rod 42 pivotally connected at one end at 41' with said segment plate 38. The other end of said toggle 60 rod 42 is slidably received within a rocking pivot stud 44 extending from the bracket 21. A coiled spring 45 under compressed tension is interposed between said pivot stud 44 and a shoulder on the rod 42 tending to hold the segment plate 38 in 65 either one of its two positions. In the full line position shown in Fig. 3, which may be termed the cocked position of the toggle 38, 42, the roller 40 of plate 38 bears against the rocking beam 33 tending to rock it clockwise. When the plate 38 70 is in its dotted line position of Fig. 3 which may be termed the uncocked position, the roller 41 of said plate 38 bears against the rocking beam 33 tending to rock it counterclockwise. The rocking movement of beam 33 is limited by one 75 end 54' thereof abutting the hub of cam collar

31, and the other end 54 thereof abutting the hub of cam collar 46, the latter being fixed to the switch handle shaft 11.

The cam collar 46 has formed in its surface a recess 47 which when it arrives opposite the end 5 54 of said rocking beam 33 and assuming said toggle 38, 42 to be in cocked position, allows said beam to rock clockwise sufficient to release the latch pawl 35 from the arm 27 of the trip member 20 as shown in Fig. 4. The switch handle 10 and 10 its shaft 11 are limited in movement between on and off position by means of a stop lug 50 fixed to the bracket 21 and coacting stop lugs 48 and 49 which are fixed in the handle shaft 11. A retractable pawl 51 is pivoted at 52 upon the cam 15 collar 46 and a spring 53 is arranged to normally hold said pawl 51 outwardly from said cam collar in the position shown in Fig. 3. The cam collar 46 is suitably recessed to permit said pawl 51 being depressed therein so that it does not substantially project from the surface of said cam collar 46. The functional purpose of said pawl 51 is for throwing the toggle 38, 42 from its dotted line or uncocked position to full line or cocked position as shown in Fig. 3 whenever the handle 10 20 25 is operated from on to off position. On the other hand, a revolution of the reset shaft 26 in the direction of the arrow for resetting the register to zero carries the cam 32 against rollers 39 and 40 of said plate 38 and acts to throw the toggle 38, 30 42 from its full line to its dotted line position as shown in Fig. 3. It will be understood that the cam 32 lies in a plane behind the beam 33 so as to act against the rollers 39, 40 and stud 30 without interference with said beam 33. 35

The operation of the above described mechanism is as follows: Assume that the parts are as shown in full lines in Fig. 3 wherein the motor switch handle is in off position and actuating mechanism for the bell is latched in inactive position. This is the position of the parts after a dispensing operation and after the switch handle has been turned off and nothing further has been done by the attendant. In other words, the attendant has not yet reset the register to zero and 40 the toggle is in its cocked position ready for 45 action.

Under such circumstances the attendant should properly reset the register before starting the motor for a new dispensing operation. If he fails 50 to do this and turns the switch handle on the parts will take the position shown in Fig. 4 where it will be seen that bell actuating mechanism is making the bell ring. This is due to the fact that the toggle 38, 42 has been left in its right hand 55 or cocked position tending to rock the beam 33 clockwise. When the recess 47 arrives under the end 54 of the beam 33, the latter rocks sufficiently 60 to remove latch 35 and release the trip member 20 whereby the latter through its link 19 swings 65 the bell support 17 to bring the bell wheel 15' into running contact with the rotating stub shaft 15 of the motor for ringing the bell.

The ringing of the bell warns the attendant 70 that he has failed to reset. There are two ways for stopping the ringing of the bell; first, the attendant may operate the switch handle 10 to turn off the motor and thereby stop the drive to the bell, and second, the attendant may operate the reset handle 25 to reset the register and shift 75 the toggle to its uncocked position. The revolution of the reset shaft 26 causes the cam 32 to throw the toggle 38, 42 to its left hand or uncocked position as shown in Fig. 5. The cam 32 acting against lug 30 also rocks the trip member 75

20 to swing the bell wheel 15' away from running contact with the stub shaft 50 and at the same time latches said trip member 20 in said holding position as shown in Fig. 5.

5 While it is possible to operate the reset shaft for resetting the register either before or after the motor switch is turned on, the proper way of operating the apparatus so that the bell signal will not be given is for the attendant when the 10 switch handle 10 is off as shown in Fig. 3, to first operate the reset. This action throws the toggle 38, 42 to its uncocked or dotted line position in Fig. 3. Thereafter when the switch handle 10 is turned on the parts will take the position 15 shown in Fig. 5, wherein the bell actuating mechanism remains latched in holding position with the bell out of action.

The reason for making the pawl 51 yieldingly retractable from its projected position as shown in 20 Fig. 3 is that when the attendant operates the reset shaft before turning on the motor switch, the toggle 38, 40 is thrown to its dotted line position in Fig. 3. The subsequent turning on of the motor switch handle will cause the 25 retractable pawl 51 to swing into its recess in passing the dotted line position of roll 41 and avoid throwing the toggle over to its right hand position during this on movement of the switch handle 10. In this way the bell actuating mechanism trip 30 member 20 will continue to be held in its latched holding position when the switch handle is turned on after a previous reset operation.

What I claim is:

1. In liquid dispensing apparatus of the type 35 having a driving shaft and a pump for establishing flow, a register to indicate the quantity of liquid dispensed, and a reset device for zeroizing said register in combination, a control handle movable to on and off positions corresponding 40 to the starting and stopping of said flow, a signal device comprising bell ringing means adapted for an operative connection with said shaft, spring actuated means for making said bell ringing means operative comprising a trip member 45 which has a holding position to hold said bell ringing means inactive, means operated by the movement of said control handle to on position to release said trip member and render said bell ringing means operative, and means actuated by 50 the operation of said reset device prior to the on position movement of said control handle to prevent a subsequent on position movement of said handle from releasing said trip member.

2. In liquid dispensing apparatus of the type 55 having a driving shaft and a pump for establishing flow, a register to indicate the quantity of liquid dispensed, and a reset device for zeroizing said register in combination, a control handle movable to on and off positions corresponding 60 to the starting and stopping of said flow, a signal device comprising bell ringing means adapted for an operative connection with said shaft, spring actuated means for making said bell ringing means operative comprising a trip member which 65 has a holding position to hold said bell ringing means inactive, means operated by the movement of said control handle to on position to release said trip member and render said bell ringing means operative, and means actuated by the op-

eration of said reset device to restore a released trip to its holding position.

3. In liquid dispensing apparatus of the type having a driving shaft and a pump for establishing flow, a register to indicate the quantity of liquid dispensed, and a reset device for zeroizing said register in combination, a control handle movable to on and off positions corresponding to the starting and stopping of said flow, signal means, spring actuated means for rendering said signal means operative comprising a trip member which has a holding position to hold said signal means inactive, cocking mechanism adapted when released from its cocked position to release said trip member and render said signal means 15 operative, means operated by the movement of said control handle to off position to place said cocking mechanism in cocked position, and means operated by the movement of said control handle to on position to release said cocking mechanism 20 from its cocked position.

4. In liquid dispensing apparatus of the type having a driving shaft and a pump for establishing flow, a register to indicate the quantity of liquid dispensed, and a reset device for zeroizing said register in combination, a control handle movable to on and off positions corresponding to the starting and stopping of said flow, signal means, spring actuated means for making said signal means operative comprising a trip member 30 which has a holding position to hold said signal means inactive, cocking mechanism adapted when released from its cocked position to release said trip and render said signal means operative, means operated by the movement of said control 35 handle to off position to place said cocking mechanism in cocked position, means operated by the movement of said control handle to on position to release said cocking mechanism from its cocked position, and means actuated by the operation of 40 said resetting device subsequent to the on position movement of said handle to restore said trip to its holding position.

5. In liquid dispensing apparatus of the type having a driving shaft and a pump for establishing flow, a register to indicate the quantity of liquid dispensed, and a reset device for zeroizing said register in combination, a control handle movable to on and off positions corresponding to the starting and stopping of said flow, signal 45 means, spring actuated means for making said signal means operative comprising a trip member which has a holding position to hold said signal means inactive, cocking mechanism adapted when released from its cocked position to release said 50 trip and render said signal means operative, means operated by the movement of said control handle to off position to place said cocking mechanism in cocked position, means operated by the movement of said control handle to on position 55 to release said cocking mechanism from its cocked position, and means actuated by the operation of said resetting device prior to the on position movement of said handle to restore said cocking mechanism to its uncocked position whereby it will 60 not be released by a subsequent on position movement of said handle.

WARREN H. DELANCEY.
